UNITED STATES PATENT OFFICE.

WILLIAM C. HARTMANN, OF PHILADELPHIA, PENNSYLVANIA, ASSIGNOR OF
ONE-HALF TO JOHN J. MOSSUP, OF SAME PLACE.

DIE-STOCK.

SPECIFICATION forming part of Letters Patent No. 300,604, dated June 17, 1884.

Application filed October 11, 1883. (No model.)

To all whom it may concern:

Be it known that I, WILLIAM C. HARTMANN, of Philadelphia, Pennsylvania, and a citizen of the United States, have invented certain 5 Improvements in Die-Stocks, of which the following is a specification.

The objects of my invention are, first, to improve the construction of the cutting-die; secondly, to permit the ready insertion of the die 10 into or its removal from the stock, and to hold it securely in place therein when in use; thirdly, to provide simple and efficient pawl-and-ratchet mechanism for operating the die; and, 15 fourthly, to insure the proper guidance of rods or tubes of different sizes to be threaded.

In the accompanying drawings, Figure 1, Sheet 1, is a face view of the stock; Fig. 2, a longitudinal section of the same; Fig. 3, Sheet 20 2, a rear view; Fig. 4, a transverse section on the line 1 2; Figs. 5 to 12, Sheet 3, views illustrating my improved cutting-die and the novel mode of making the same; Figs. 13 and 14, Sheet 1, detached views of the pawls and their operating-stud; and Fig. 15, a modification.

25 The casing of the stock consists of a ring, A, having at the back an internal flange, *a*, and at each side a projecting stud, *b*, to which the handles B of the stock are secured.

The die-holder consists of the two circular 30 plates, D D', the former fitting snugly but so as to turn freely in the ring A, and resting on the flange *a*, the plate D' bearing against the rear edge of the ring, and being recessed for the reception of the flange *a*, so that when the two 35 plates are bolted together they are laterally confined to the ring, but free to rotate in the same.

The dies F F are fitted to a central elongated opening in the holder, and consist, as 40 usual, of threaded blocks, which, however, are made in the peculiar manner described hereinafter, and forming part of my invention. The centering of the dies in the holder is effected by opposite set-screws *c* *c*, carried by 45 the holder and bearing upon the outer ends of the said dies, the screws also serving, in a measure, to retain the dies in the holder, for it should be understood that the dies are simply slipped into place from the top or face of the 50 stock, so that they can be readily inserted or

removed without the necessity of first removing a retaining cover-plate. Reliance for the retention of the dies in the holder is, however, mainly placed upon a bar, *d*, Figs. 2 and 4, the inner edge of which is adapted to grooves *e* in the sides of the dies F, the outer edge of the bar being acted upon by taper screws *f*, by turning which the bar may be forced into the grooves *e*, so as to retain the dies, or may be permitted to leave the same when it is desired 60 to detach the dies.

In order to permit the turning of the set-screws *c* without detaching the die-holder, openings *g* are made in the ring A, so that by turning the holder until the screws *c* are in 65 line with these openings said screws may be readily operated by a suitable tool introduced through the openings.

The periphery of the plate D of the die-holder has teeth *h*, abrupt on both faces, and 70 one of the projections *b* is made tubular for the reception of two sliding pawls, G G', the outer ends of which are acted upon by springs *i*, the inner ends of the pawls being beveled—that of the pawl G in one direction and that 75 of the pawl G' in the opposite direction—so that one pawl is adapted to engage with the teeth *h* and turn the die-holder when the ring A is turned to the right, and the other pawl 80 when the ring is turned to the left, these devices thus constituting a duplex pawl-and-ratchet mechanism. It is necessary, however, to withdraw and retain one pawl when the other is in action, and for this purpose various means may be employed, the simplest being set-screws passing through the projection *b* and adapted to bear upon or to enter recesses in the pawls when the latter are retracted, as 85 shown in Fig. 15. For the ready operation of the pawls, however, I prefer the device 90 shown in Figs. 1, 2, and 14, this device consisting of a knob, H, adapted to a bearing in the projection *b*, and having a pin, *k*, adapted to engage with slots *m* in the pawls, the pin and slots being so arranged that the turning 95 of the knob in one direction or the other to the required extent will effect the projection of one pawl and the retraction of the other. Thus on reference to Fig. 2 it will be observed that if the knob H is turned in the di- 100

rection of the arrow, the pin *k* will first depress the pawl *G'*, and will then pass from the slot *m* of said pawl to that of the pawl *G*, and on continuing the movement will effect the 5 raising or retraction of said pawl *G*.

A spring-catch, *j*, adapted to notches in the knob, or some equivalent device, should be employed to retain the said knob in its extreme positions; otherwise the springs *i* will 10 depress both pawls.

The pawls may be rectangular in cross-section; but as this would necessitate the formation of a rectangular opening in the projection *b*, I prefer to use pawls of the character shown 15 in Fig. 13, these pawls being formed by simply severing longitudinally a round bar with tapered end. To prevent the pawls from turning in the projection *b*, one of said pawls has a groove, *n*, to which is adapted the point 20 of a pin, *n'*. (See Fig. 2.)

When it is not desired to use the ratchet mechanism of the stock, the die-holder may be locked to the ring *A* by a set-screw, *J*.

On the rear of the plate *D'* of the die-holder 25 is a tubular projection, *K*, to which is fitted a ring, *K'*, having projections *q*, corresponding with the bases of the threads in the cutting-dies, and serving as guides for the rod or bar upon which a thread is to be cut. This 30 ring *K'* is detachable, so that rings of different sizes adapted to guide-rods of different diameters may be used, the rings having tongues *s*, adapted to a groove in the projection *K*, so that they are prevented from turning, and the maintenance of their projections *q* in line with the cutting-bits of the die is insured, the ring being held in position longitudinally by a set-screw.

The construction of the improved dies *F*, 40 which I use in the stock, is shown in Figs. 5 to 12, Sheet 3. Each die has on the inner face two cutting-bits, *w w*, there being a recess, *x*, outside of each bit, and a recess, *y*, between the two. The usual plan of making dies of this 45 class is to take a block of the character shown in Fig. 5; to first drill a central hole in the same, as indicated by the dotted circle 1; then to thread the opening thus formed, as shown by the circle 2; then to drill the four holes 50 indicated by the dotted circles 3, and finally to sever the block on the central line, 4, so as to form two dies with the desired cutting-bits *w* and recesses *x* and *y*. The objection to this plan is that the drilling of the holes 3 leaves 55 the teeth of the bits *w* with ragged ends; hence it is necessary to file out the recesses *x* and *y*, the character of the latter recess (it being more than a half-circle) precluding the use of a milling-tool for this purpose. The sharpening 60 of the bits of a die of this character is also a very difficult operation—so much so, in fact, that the bits, when they become dull, are generally thrown away. These objections I overcome by making each die *F* in two parts, 65 *t* and *t'*, each half having one of the bits *w*, and the recess *y* being formed partly in one

half and partly in the other, as shown in Figs. 6, 7, and 8, so that when the two parts of the die are secured together by the bolt *u* the die, so far as the cutting-bits and recesses are concerned, will be similar to one made in the ordinary way. The halving of the dies, however, permits me to use a milling-tool to true the recess *y*, as well as the recesses *x*; hence the manufacture of the die is materially facilitated, 70 a better die is produced, and the sharpening of the bits when they become dull can be readily accomplished.

In making my improved dies I take two blocks, *W W*, Fig. 9, and, after bolting the 80 same together, form the central threaded opening, as shown in Fig. 10, and then sever the block on the central line, 4. The bolts are then removed so as to leave four segments or half-dies of the character shown in Fig. 11, in 85 which segments the desired recesses can be readily formed by means of a suitable milling-tool, as will be seen on reference to the dotted lines in said figure. It is preferable to form on one half of the die a tongue, *v*, and on the 90 other half a groove, *v'*, so as to aid the bolt *u* in preventing the halves of the die from shifting their position laterally, a modification of this idea being that shown in Fig. 12, in which a recess is milled in each half of the die, these 95 recesses coinciding when the halves are bolted together and forming an opening for the reception of a retaining-pin, *v''*.

I claim as my invention—

1. The combination of the die-holder, the 100 dies having grooves *e*, the retaining-bar *d*, adapted to said grooves, and the taper screws *f*, for adjusting said bar, as set forth.

2. The combination of the outer ring or casing, *A*, the die-holder having teeth *h*, and the 105 spring-pawls *G G'*, adapted to act upon said teeth, and sliding in a projection of the ring, with means, substantially as described, for retaining either of said pawls in a retracted position, as set forth.

3. The combination of the ring or casing *A*, the die-holder having teeth *h*, the spring-pawls *G G'*, having grooves *m*, and the knob *H*, having a pin, *k*, adapted to said grooves, as set forth.

4. The combination of the ring or casing *A*, the die-holder having teeth *h*, the spring-pawls *G G'*, having grooves *m*, the knob *H*, having a pin, *k*, and means for retaining said knob in the positions to which it is adjusted, 110 as set forth.

5. The combination of the ring or casing *A*, the die-holder having teeth *h*, and the spring-pawls *G G'*, of semicircular cross-section, whereby they are adapted to a circular opening in 115 the casing, as set forth.

6. The within-described cutting-die, made in halves bolted together, as described, and having cutting-bits *w*, opposite recesses *x*, and central recesses, *y*, the latter being bounded 120 by true segments extending to the points of the teeth of the bits *w*, as set forth.

7. The within-described cutting-die, made in halves bolted together, and having a tongue-and-groove connection, said die having cutting-bits w , opposite recesses x , and central recesses, y , the latter being bounded by true segments which extend to the points of the teeth forming the bits w , as set forth.

8. The mode described of making dies for die-stocks, said mode consisting in first bolting together two blocks, W W' , forming a central threaded opening therein, transversely severing the compound block on a line pass-

ing centrally through the opening, then separating the parts W W' , and finally milling recesses x and y in each of the segments thus produced, so as to form thereon a cutting-bit, w , as set forth.

In testimony whereof I have signed my name to this specification in the presence of two subscribing witnesses.

WM. C. HARTMANN.
